CLAIM

The ornamental design for a movable table leg, as shown and described.

DESCRIPTION

FIG. 1 is view in side elevation of a movable table leg showing my new design;

FIG. 2 is a view in side elevation opposite to the view shown in FIG. 1;

FIG. 3 is a view in end elevation thereof;

FIG. 4 is a view in end elevation opposite of that shown in FIG. 3;

FIG. 5 is a top plan view thereof; and,

FIG. 6 is a bottom plan view thereof.

The broken lines are for environmental purposes only and form no part of the claimed design.
